UNITED STATES PATENT OFFICE.

CHARLES A. CARSCADIN, OF CHICAGO, ILLINOIS, ASSIGNOR, BY MESNE ASSIGNMENTS, TO AMERICAN STEEL FOUNDRIES, OF CHICAGO, ILLINOIS, A CORPORATION OF NEW JERSEY.

YOKE FOR DRAFT-GEAR.

1,350,436.

Specification of Letters Patent. Patented Aug. 24, 1920.

Application filed March 30, 1917. Serial No. 158,717.

To all whom it may concern:

Be it known that I, CHARLES A. CARSCADIN, a citizen of the United States, residing at Chicago, in the county of Cook and 5 State of Illinois, have invented certain new and useful Improvements in Yokes for Draft-Gears, of which the following is a specification.

This invention relates to yokes for rail- 10 way draft gears and has for its object the provision of a yoke having means to retain the drawbar butt and receive stresses there- from without the aid of a key passing through the drawbar butt and constructed 15 to permit insertion and removal of the drawbar butt without separating the yoke from the car frame.

A further object of my invention is the provision of a yoke having a separable and 20 adjustable bottom member permitting inter- changeable use of drawbar butts of different sizes therewith.

Further objects and advantages of my invention reside in the various combinations 25 hereinafter described and claimed as will be more apparent as the invention is better understood by reference to the following specification when read in connection with the accompanying drawing, illustrating the 30 preferred embodiments thereof, in which—

Figure 1 is a side elevation of a yoke according to my invention;

Fig. 2 is a section on the line 2—2 of Fig. 1;

Fig. 3 is a front end elevation of the yoke illustrated in Fig. 1;

Fig. 4 is a horizontal section through a slightly different form of yoke;

Fig. 5 is a rear end elevation of the yoke 40 illustrated in Fig. 4;

Fig. 6 is a side elevation of the yoke illustrated in Fig. 4;

Figs. 7 and 8 are details in elevation of different means for dividing the yokes illustrated in Figs. 1 and 6 medially thereof to 45 form tandem yokes;

Fig. 9 is a section on the line 9—9 of Fig. 8;

Fig. 10 is a side elevation of a yoke em- 50 bodying adjusting means to permit inter- changeable use of drawbar butts of different sizes, and

Fig. 11 is an inverted plan on a somewhat smaller scale of a portion of the structure 55 illustrated in Fig. 10.

Referring to Figs. 1 and 3, inclusive, of the drawing 1 indicates a top member provided with a lug 2 at its forward end adapted to be engaged by a shoulder on the butt 3 of the drawbar 4. The top member 1 is 60 further provided with integral side walls 5 and 6 at each end thereof forming the ends of the yoke, the side walls 5 at the forward end being adapted to restrain lateral movements of the drawbar butt 3. In the form 65 of my invention illustrated in Fig. 1 the side walls 6 at the rear end of the yoke are provided with a connecting web 7 at their lower ends. A bottom member 8 is provided at its forward end with an integral lug 9 70 adapted to be engaged by a shoulder on the butt 3 and which co-operates with the lug 2 on the top member to receive pulling stresses from the draw-bar 4. At its rearward end the bottom member 8 is provided 75 with an integral lug 10 engaging the web 7 to hold the bottom member against forward movement when the structure is assembled and in use. A lug 11 on the upper side of the bottom member 8 bears against 80 a follower plate (not shown).

The side walls 5 are provided with inwardly directed lugs 12 which limit downward movement of the bottom member 8 when released and obviously these lugs may 85 be connected to form a continuous web if desired. A pin 13 is disposed through openings in the side walls 5 beneath the bottom member 8 to hold the latter in operative position as illustrated in Fig. 1. By 90 removing the pin 13 the bottom member is permitted to drop sufficiently to allow the butt 3 of the drawbar to pass between the lugs 2 and 9. The bottom member when released will rest upon the lugs 12 and may 95 be raised into operative position and again secured by the pin 13 when the drawbar has been repaired or replaced. Any suitable means may be employed to secure the pin 13 in position.

Referring to Figs. 4, 5 and 6 of the drawing a top member 14 is provided at its forward end with a lug 15 and side walls 16 and 17 at its front and rear ends, respectively, as in the previously described form of my 105 invention. The side walls 16 are connected by a web 18' while the side walls 17 are provided with openings to receive a pin 18 which is held in position by any suitable means. A bottom member 19 rests on the 110

pin 18 and is provided at its forward end with a lug 19' coöperating with the lug 15 on the top member 14 to receive pulling stresses from the drawbar. The bottom member 19 is provided beneath the lug 19' with a downwardly directed portion 20 which normally rests on the web 18'. At its forward end the bottom member 19 is provided with laterally projecting lugs 21, engaging the rear edges of the side walls 17 to hold the bottom member 19 against forward movement when the structure is assembled and in use. By withdrawing the pin 18 the rear end of the bottom member 19 may be dropped sufficiently to permit the lugs 21 to clear the rear edges of the side walls 17 whereupon the bottom member may be moved forwardly until the downwardly projecting portion 20 clears the web 18'. The lug 19' is then spaced sufficiently from the lug 15 to permit withdrawal of the drawbar which may be again assembled with the yoke by a reversal of the operations described.

25 My invention as hereinbefore described may be embodied in tandem as well as in single spring yokes and I have illustrated in Figs. 7, 8 and 9 two forms of dividing walls. Referring to Fig. 7 the top member 30 is indicated at 22 and the bottom member at 23, the latter being provided medially thereof with an upstanding lug 24. The top member 22 is provided with two depending integral plates 25 adapted to engage both sides of the lug 24. In Figs. 8 and 9 the top and bottom members are indicated at 26 and 27, respectively. The top member 26 is provided with two depending integral plates 28, the lower ends of which engage recesses 29 in the bottom member 27. Either of the constructions described may be embodied in the yokes illustrated in Figs. 1 and 6 to provide tandem yokes, preserving all the advantages of my invention as applied to single spring yokes.

Referring to Figs. 10 and 11 of the drawing, 30 and 31 indicate respectively the top and bottom members of the yoke provided at their forward ends with lugs 32 and 33 to receive pulling stresses from the drawbar 34. The top member 30 is provided with side plates 35, 36 and 37 integral therewith at the front and rear respectively and intermediate the ends. The side plates 35, 36 and 37 are provided with vertically spaced openings to receive pins 38 which support the bottom member 31 in operative position. The pins 38 may be prevented from accidental withdrawal by any suitable means.

60 By adjusting the pins 38 in one or the other of the sets of openings the bottom member 31 may be adjusted relatively to the top member 30 so that drawbars having butts of different dimensions may be employed interchangeably with the yoke. The bottom

member 31 is provided at its rear end with laterally extending lugs 39 which engage the rear edges of the side plates 36 and restrain the bottom member from forward movement under the drawbar stresses. Obviously the intermediate plates 37 may be omitted where a single spring yoke is desired, the form of the yoke illustrated being designed for use with double springs. The intermediate plates 37 may also be arranged as illustrated in Fig. 7 in which event the bottom member 31 would be supported by pins 38 at the front and rear ends only of the yoke.

From the foregoing it will be readily understood that I have perfected a yoke from which the butt of the drawbar may be readily withdrawn when desired without removing the yoke from the car frame, it being necessary only to withdraw the fastening pins and drop the bottom member until the lug at the forward end thereof clears the shoulder on the butt of the drawbar and permits the latter to drop sufficiently to disengage the upper shoulder thereof from the lug at the forward end of the top member. I have provided, moreover, a yoke with which drawbars having butts of different dimensions may be employed interchangeably.

It will be apparent that various changes may be made in the form, construction and arrangement of the parts without departing from the spirit and scope of the invention or sacrificing any of its material advantages, the forms hereinbefore described being merely preferred embodiments thereof.

I claim:

1. A yoke for draft gears comprising separable top and bottom members both provided with integral lugs at their forward ends to receive pulling stresses from the drawbar, said top member being provided with pairs of side walls integral therewith at both ends, a plurality of vertically spaced openings in each side wall, the openings in the respective sides of each pair being oppositely disposed, and pins adapted to be selectively disposed in said openings to maintain said bottom member in operative position.

2. A yoke for draft gears comprising separable top and bottom members, and means for adjustably securing said bottom member to said top member in one of a plurality of positions spaced relatively thereto.

3. A yoke for draft gears comprising separable top and bottom members, said top member being provided with pairs of side walls integral therewith at both ends and intermediate said ends, and means for adjustably securing said bottom member in one of a plurality of positions spaced relatively to said top member.

4. A yoke adapted for shouldered engage-

ment with a shouldered draw bar butt, said yoke being adaptable to fit draw bars of different dimensions.

5. A yoke of the vertical type having upper and lower arms and means for engaging the butt of a draw bar, the portions of said yoke carrying said means being relatively adjustable and adapted to coöperate with draw bar butts of different sizes.

10 6. A yoke including elements having shoulders thereon adapted to coöperate with the upper and lower shoulders of a standard draw bar butt, said elements being relatively vertically adjustable to thereby adapt the 15 yoke for coöperation with different sized draw bar butts.

7. A yoke having a hood at its forward end within which a shouldered draw bar butt is adapted to be received, said yoke including means for adjusting the interior 20 height of the hood to thereby accommodate butts of different vertical dimensions.

8. A two-part yoke, each part having a shoulder at its forward end adapted to co-operate with a shoulder of a draw bar, and 25 means permitting adjustment of said shoulders relatively vertically for engagement with draw bar butts of different sizes.

9. A yoke for railway draft riggings comprising an upper and a lower element, 30 and means at the front and rear ends of said yoke for holding the parts of the yoke in various adjusted positions.

10. A yoke for railway draft riggings comprising two elements, each element having a transverse shoulder at its forward end adapted to coöperate with the shoulders of a draw bar butt, and means for securing the front and rear ends of said parts in different 35 adjusted positions.

CHARLES A. CARSCADIN.
